UNITED STATES PATENT OFFICE.

WILLIAM J. N. ALDRIDGE, OF SPRINGFIELD, MISSOURI.

BRAKE-SHOE BRACE.

No. 894,309.

Specification of Letters Patent.

Patented July 28, 1908.

Application filed April 16, 1908. Serial No. 427,495.

To all whom it may concern:

Be it known that I, WILLIAM J. N. ALDRIDGE, a citizen of the United States, residing at Springfield, in the county of Greene and State of Missouri, have invented certain new and useful Improvements in Brake-Shoe Braces; and I do declare the following to be a full, clear, and exact description of the invention, such as will enable others skilled in the art to which it appertains to make and use the same.

This invention relates to brake shoes and has for its object to provide a novel brake shoe in which is placed peculiar means bracing the same.

Another object is to provide in a cast brake shoe efficient means for bracing a shoe and for carrying the loop by which the shoe is attached to the brake beam.

For these and still other objects which will appear as the description proceeds, the invention consists of certain novel features, arrangements and combinations of parts of which the herein described brake shoe brace back is one of many possible embodiments.

While herein the description refers to minute details of the invention, the invention is not limited to these as the details of construction and combination may be greatly varied without departing from the spirit and scope of the invention.

In the annexed drawings forming a part of this specification in which like reference characters refer to like parts throughout the several views and which are for illustrative purposes only and therefore not drawn to any particular scale, Figure 1 is a top plan view of the shoe back; Fig. 2 is a side view of the same; Fig. 3 is a bottom view; Fig. 4 is a sectional view taken on the line 4—4 of Fig. 1; Fig. 5 is a top plan view showing a brake shoe with the brace back applied; and Fig. 6 is a side view of the brake shoe, parts being shown in section.

Referring more particularly to the drawings, the preferred embodiment of the present invention is illustrated as comprising a brace back composed of a plate 1 of steel or the like of any convenient dimensions, said plate being cut longitudinally to form a plurality of strips joined by a yoke 2 at the ends. Certain of these strips for instance the outer strips 3 and the mid strip 4 are curved to conform to the rear face of the brake shoe. The inner strips 5 are pressed inwardly to

form arcs substantially parallel to the strips 3 and 4 and connect with said yokes by means of the curved portion 6. The top loop 7 is provided with laterally outstanding ends 8 adapted to engage under the said strips 3 and is securely fastened thereto by means of bolts 9. The brake shoe 10 is cast on said back brake as is clearly shown in Figs. 5 and 6, in such a manner that the strips 3 and 4 are flush with the outer face of the brake shoe and the strips 5 are embedded intermediate its faces, the loop 7 projecting therefrom.

A brake shoe constructed after the manner described is used and applied as an ordinary brake shoe.

Having thus described my invention, what I claim as new and desire to secure by Letters-Patent, is:

1. A brake shoe back comprising a plate 75 of metal cut into strips all of which are bent to form arcs and are connected at their ends and a loop secured to certain of said strips.

2. A brake shoe brace comprising a metal plate having slits cut longitudinally thereof, 80 nearly from end to end, whereby are formed longitudinal strips, all of which are substantially arc-shaped, having substantially the same center of curvature, certain of said strips being bent inwardly nearer said center than others of said strips and a loop secured to certain of said strips.

3. In combination a metal plate longitudinally slitted nearly from end to end, whereby are formed a plurality of longitudinal strips connected by an end yoke, all of said strips being arc-shaped and having substantially the same axis of curvature, the outside and mid strips being further from the axis of curvature than the intermediate strips; loops having laterally extending ends engaging under said outside strips, bolts clamping the same together and a metal shoe cast on said brace, the outer faces of said shoe being substantially flush with the said 100 outside and midway strips, said intermediate strips being intermediate the outer and inner faces of said shoe.

In testimony whereof I have hereunto set my hand in presence of two subscribing 105 witnesses.

WILLIAM J. N. ALDRIDGE.
